WILHELM HEFTI, OF WINTERTHUR, SWITZERLAND, ASSIGNOR TO THE FIRM: SULZER
FRÈRES SOCIÉTÉ ANONYME, OF WINTERTHUR, SWITZERLAND

SHIP WITH AEROPLANE DECK

Application filed September 29, 1928, Serial No. 309,146, and in Switzerland November 25, 1927.

This invention relates to steam or motor propelled ships provided with a deck to accommodate aeroplanes.

According to this invention means are provided for discharging the smoke or exhaust gases from the engine in a lateral direction below the level of the aeroplane deck more especially when the latter is to be used to receive or launch an aeroplane. Preferably the ship is provided with telescopic or like disappearing funnels which, when extended, enable the smoke or exhaust gases to be discharged in the usual manner.

The lateral discharge shafts may be formed as branches from the above chimneys or funnels which are preferably provided with or incorporated in some known form of spark catcher and in a convenient arrangement an operative connection is provided between the lateral branches and the collapsible funnels which ensures these branches being automatically opened when the funnels are lowered and vice versa.

The disappearing funnels are in some cases furnished with small openings to allow sufficient smoke or exhaust gases to escape in an upward direction through the aeroplane landing deck so as to indicate the direction of the wind.

Two constructions according to this invention are diagrammatically illustrated by way of example in the accompanying drawings, in which

Figure 1 is a side elevation of the ship provided with an aeroplane deck,

Figure 2 is a cross-section on the line 1—1 of Figure 1 on an enlarged scale, and

Figures 3 and 4 show in vertical section and plan respectively on an enlarged scale a special form of collapsible funnel.

The ship diagrammatically illustrated is provided with an aeroplane landing and launching deck 1 and is fitted with four Diesel engines 2, the exhaust gases of which escape into the atmosphere through silencers 3 and vertical exhaust pipes 4. The exhaust pipes are provided with end pieces or funnels 5 which can be lowered under the aeroplane deck and further communicate with lateral branches 6 through which the smoke or ex-

haust gases can be discharged in a substantially horizontal direction below the level of the aeroplane deck when the funnels 5 are lowered. The funnels 5 are so built that when they are raised they discharge the exhaust gases above the heads of the men working on the aeroplane deck 1 and in their lowest position they are flush with the level of the deck and so form no obstacle to the free passage of the aeroplanes.

These funnels are preferably mounted in spark arresters 7 into which they are lowered and with which the lateral branches connect. The lateral branches 6 are furnished with flap valves or dampers 8 which are closed when the funnels are raised and are opened when the funnels are lowered, preferably some positive connection being provided between the funnels and the valves to ensure that they are automatically operated in the desired manner when the funnels are moved.

Normally the funnels occupy their raised position so that the flap valves 8 controlling the lateral branches 6 are closed but when aeroplanes are to be handled the funnels 5 are lowered and the valves 8 opened.

The spark arresters are furnished in the well known manner with helical partitions so as to impart a rotary motion to the smoke or exhaust gases with the result that the sparks are separated by the centrifugal force thus produced, although it will be understood that any known form of spark arresters may be employed.

In the particular construction illustrated in Figures 3 and 4, the funnels are furnished with radial openings for the outlet of the smoke or exhaust gases which for the main part thus leave the funnels in a lateral direction, but in addition the upper ends of the funnels are furnished with flat plates 10 adapted when lowered to lie flush with the level of the aeroplane deck and provided with relatively small perforations so that even when the funnels are lowered some smoke still escapes upwards and indicates to the pilot of any aeroplane wishing to land on deck the exact direction of the wind.

I claim:

1. In a ship having an aeroplane deck the

combination of the driving engines and telescopic funnels adapted with lateral branch funnels to be closed at will.

2. In a ship having an aeroplane deck the combination of the driving engines with means for discharging the exhaust gases in a lateral direction below the level of the aeroplane deck and with telescopic funnels, through the top of which these gases can be discharged when the funnels are in their raised position.

3. In a ship having an aeroplane deck the combination of the driving engines with means for discharging the exhaust gases in a lateral direction below the level of the aeroplane deck and with disappearing funnels provided with a spark arresting device, through the top of which these gases can be discharged when the funnels are in their raised position.

4. In a ship having an aeroplane deck the combination of the driving engines and disappearing funnels with lateral branch funnels and means for automatically opening the branch funnels when the disappearing funnels are lowered.

5. In a ship having an aeroplane deck the combination of the driving engines with means for discharging the exhaust gases in a lateral direction below the level of the aeroplane deck and with the disappearing funnels provided with openings through which some gases can still escape to indicate the direction of the wind even when the said funnels are in their lowered position.

In testimony whereof I have affixed my signature.

WILHELM HEFTI.
